UNITED STATES PATENT OFFICE.

JOHN B. GRAVELLE, OF ASBURY PARK, NEW JERSEY.

RAILWAY-BRAKE.

1,108,900.

Specification of Letters Patent.

Patented Sept. 1, 1914.

Application filed June 30, 1913. Serial No. 776,644.

To all whom it may concern:

Be it known that I, JOHN B. GRAVELLE, citizen of the United States, residing at Asbury Park, in the county of Monmouth and 5 State of New Jersey, have invented certain new and useful Improvements in Railway-Brakes, of which the following is a specification.

This invention relates to emergency 10 brakes for railway cars, and has as its object to provide an emergency brake which may be readily and quickly applied by the engineer and which will act to bring the train of cars almost instantly to a stand- 15 still.

Another aim of the invention is to provide an emergency brake system which may be set throughout the entire length of the 20 train by the opening of a single valve in the engine cab.

Another aim of the invention is to so construct the brake system that the brakes will not be liable to become accidentally set and which will at no time interfere with the 25 ordinary air brake system.

The brake is of that type including a shoe normally supported above the track rails but adapted to be lowered on to the rails in advance of the wheels when it is desired to 30 apply the brake, and one feature of the invention resides in the provision of means for supplying sand to the rails beneath the shoe or shoes when the brake is set so that the train may be more quickly brought to a 35 standstill.

Another feature of the invention resides in the provision of means for limiting the movement of the shoes to position beneath the wheels of the car and for cushioning the 40 shock incident to the setting of the shoes.

In the accompanying drawings: Figure 1 is a view in side elevation of a railway car equipped with the brake embodying the present invention. Fig. 2 is a similar view 45 on a large scale, illustrating only a portion of the length of the car. Fig. 3 is a view similar to Fig. 2 but illustrating one of the brake shoes set. Fig. 4 is a detail view partly in side elevation and partly in section, illustrating the means for releasing the shoes. Fig. 5 is a perspective view of 50 one of the shoes. Fig. 6 is a vertical longi-

tudinal sectional view therethrough. Fig. 7 is a vertical transverse sectional view.

Corresponding and like parts are referred 55 to in the following description and indicated in all the views of the accompanying drawings by the same reference characters.

In the drawings, the body of the car is indicated in general by the numeral 1 and 60 the trucks are indicated by the numeral 2 and are supported upon the usual wheels 3. The treads of the wheels 3 are of the ordinary form and the rails 4 are of the ordinary type. 65

The brake shoe is clearly illustrated in 70 Figs. 5, 6 and 7 of the drawings, and it will be understood that one of these shoes is to be provided for each truck at each side thereof, and each shoe being located in advance of the corresponding forward wheel 75 of the respective truck. The shoes are preferably cast and each includes a body portion indicated by the numeral 6 and decreased in thickness in the direction of its end which

enters between the wheels and the rails, as clearly shown in Fig. 6 of the drawings, and as indicated by the numeral 7. The body portion 6 of each shoe is struck up longitudinally medially as at 8 from a point adjacent the other end of the shoe to a point approximately midway between the ends of the shoe. In striking up the shoe in the manner stated, a channel 9 is formed extending longitudinally medially of the under side of the said body portion 6. This channel is gradually decreased in depth to 80

ward the middle of the shoe so that sand supplied to the channel at its major end will be packed beneath the shoe and will not 85 be liable to be scattered about or jarred off from the tread of the rail. 90

As before stated, means is provided for supporting the shoe above the rails and in advance of the forward wheels of the truck, 95 and said means includes a hanger rod 10 which at its upper end is pivotally connected as at 11 to the under-frame of the car and which at its lower end is bent to form a hook 12 fitted through a relatively small 100 opening 13 formed in the body portion of the shoe adjacent its tapered end 7. The rod 10 is preferably of resilient rod material and while it will securely support this

end of the shoe when the shoe is in normal position, it is not sufficiently rigid and strong to prevent the proper placing of the shoe beneath the wheels, and in fact, upon such movement of the shoe, the bent end of the rod momentarily straightens out sufficiently to allow the rod to disengage from the shoe. The other end of the shoe is supported by means of a chain 14 connected at one end to a small clevis 15 carried by the shoe at its said end, and this chain at its other end is connected to a ring 16 to which is also connected a length of chain 17, which chain is adapted to be wound, and in fact, is normally wound upon a drum 18 also mounted upon the under-frame of the car. In order that this drum may be rotated to wind up the chain 17, there is provided a crank handle 19 fitted upon one end of the shaft for the drum. At one end the drum is provided with a ratchet head 20 with which is normally engaged a finger 21 of a rocking pawl mounted as at 22, upon the under-frame of the car. A spring 23 is arranged to bear against the finger 21 and serves to normally hold the finger in engagement with the teeth of the ratchet 20. The other arm of the rocking pawl is indicated by the numeral 24 and mounted upon the under-frame adjacent the said arm 24 is a small cylinder 25 in which is arranged a plunger 26. The plunger 26 has a stem 27 secured through the arm 24 and the base of the cylinder is provided with a compressed-air port 28 supplied by a pipe 29 which may lead from any suitable source of air supply. The pipe 29 or the sections comprising the same extends the entire length of each car and may be coupled up through out the entire train so that all of the brakes may be set. The passage of air through the pipe 29 is intended to be governed by a valve in the engine cab, which valve may be independent of the engineer's valve, or the engineer's valve may be provided with an extra port to adapt it for the connection thereto of the said pipe 29. In any event, the opening of the valve in question, will admit air under pressure to the pipe and as the air rushes into the cylinder 25 the piston 26 will be so moved as to swing the arm of the respective pawl in a direction to disengage the finger 21 from the teeth of the ratchet 20, which of course, will allow the chain 17 to unwind from the drum 18 and will permit the brake shoe to move rearwardly and downwardly until its tapered entering end engages beneath the respective forward wheel of the truck. At this point, it may be stated that if it is desired an electro-magnet may be employed in place of the cylinder and plunger.

In order to limit the movement of the brake shoe to position beneath the wheels of the truck, a chain 30 is connected to the ring

16 and to one end of a stem 31 mounted for sliding movement in a cylindrical casing 32. A spring 33 is arranged upon the stem and at one end bears against the closed end 34 of the casing and at its other end bears against a collar 35 fixed upon the said stem. A relatively short length of chain 36 is connected to the other end of the stem and is secured to the under-frame of the car as indicated at 37.

From the drawings it will be observed that two sets of brake shoes are provided beneath each car so that the brakes may be applied with efficiency whether the car be drawn one end or the other end first.

From the foregoing description, it will be apparent that when it is desired to apply all the brakes air under pressure is permitted to each pipe 29 and entering the respective cylinder 25 causes the piston 26 to move in such a manner as to rock the pawl 22 thereby bringing its finger 22 out of engagement with the teeth of the ratchet 20. Immediately upon disengagement of the pawl from the ratchet, the chain 17 will unwind from the drum 18, thereby allowing the respective brake shoe 6 to move downwardly and rearwardly until its entering or tapering end 7 engages beneath the respective wheel 3. The movement of the train will, of course, after such engagement, result in the passage of this wheel and the corresponding rear wheel of the truck on to the shoe, the shoe being of such a length that it may extend beneath both wheels at once. As soon as the shoe enters between the forward wheel and the rail, the strain imposed upon the hanger rod 10 will result in its ends 12 being momentarily straightened so as to be pulled through the opening 13 to release the forward end of the shoe. As the wheels pass on to the shoe the slack in the chain 30 is, of course, taken up and finally a pull will be exerted upon the stem 31 which pull, although sudden, will be cushioned by the spring 33 until the strain is imposed upon the chain 36.

As before stated, means is provided for supplying sand beneath the brake shoes and it has already been stated that each shoe is provided with a channel 9 on its under side by means of which sand may be supplied. To supply this channel, a pipe 38 is provided and is fitted at one end into the larger end of the channel 9 and at its other end is in communication with a sand reservoir 40, which is located at any convenient point within the car, although preferably upon the floor thereof. The pipe 38 is flexible and the normal bend in the pipe is such that a trap is formed, so to speak so as to prevent the leakage of the sand. As the shoe is lowered, however, the pipe will be straightened out, as clearly shown in Fig. 3 of the drawings, and will be inclined to such

degree as to insure of the sand being fed through it to the channel 9.

In order to insure of the proper setting of the brake shoe upon the rail, the body of the 5 shoe is provided at one lateral edge with a depending flange 41 designed to extend beside the head of the rail, as shown in Fig. 7 of the drawings. At its other edge the body 6 is provided with an upstanding flange 42 which is designed to engage against the 10 wheel in the manner shown in Fig. 2 so as to prevent lateral displacement of the shoe body 6 upon the rail. It will be observed from an inspection of Fig. 5 that the flanges 15 41 and 42 are bent gradually away from each other at the entering end of the shoe, as at 43 and 44 respectively, so as to further insure of the proper setting of the shoe upon the rail. In a like manner the flange 41 at 20 the opposite end of the shoe is slightly turned outwardly as indicated at 45 so that it will not interfere with the switch tongues and frogs.

Having thus described the invention what 25 is claimed as new is:

1. In a railway brake, a shoe, means supporting the shoe for movement to braking position, the shoe being provided with a sand passage opening at the braking face 30 thereof, a sand reservoir, and a pipe leading from the reservoir to the sand passage for the shoe and arranged to conduct the sand to said passage upon movement of the shoe to braking position, the said pipe being flexible and being arranged when the shoe is in 35 inoperative position to sag to form a trap to provide the discharge of sand when the shoe is in such position.

2. In a railway brake of the class 40 described, a shoe adapted to be applied between the rail and wheel, the said shoe being provided with a sand passage opening at its under braking face, said passage having an inlet end opening at the upper face of the 45 shoe, a pipe fitted at the last mentioned end of the passage, a sand reservoir to which the pipe is connected, the reservoir, pipe and shoe being so relatively located that when the shoe is in inoperative position, the pipe 50 will be sagged to cut off the supply of sand and when the shoe is in operative position will be approximately straight, whereby the sand will be supplied to the sand passage.

3. A shoe for a brake of the class 55 described comprising a body portion provided at one of its lateral edges with an upstanding flange and at its other lateral edge with a depending flange, the flanges being arranged to engage respectively with a wheel 60 and rail between which the shoe is adapted to be applied, the last mentioned flange being outturned at its ends.

4. A shoe for a brake of the class 65 described comprising a body portion provided at one of its lateral edges with an upstand-

ing flange and at its other lateral edge with a depending flange, the flanges being arranged to engage respectively with a wheel and rail between which the shoe is adapted to be applied, the first mentioned flange at 70 the entering end of the shoe being outturned.

5. A shoe for a brake of the class described comprising a body portion provided at one of its lateral edges with an upstanding flange and at its other lateral edge with a depending flange, the flanges being arranged to engage respectively with a wheel and rail between which the shoe is adapted to be applied, the first mentioned flange at 75 its end at the entering end of the shoe being outturned and the second mentioned flange having its ends also outturned.

6. In a railway brake of the class described, a shoe adapted to be applied between the rail and wheel, means for supporting the shoe for movement to such position, said means including a resilient hanger rod having a hooked lower end and the shoe being provided with an opening receiving the 80 said end of the rod, the said end of the rod due to its resiliency being adapted to be pulled through said opening when the shoe is lowered to braking position, and means for limiting the movement of the shoe to 85 such position.

7. In a railway brake of the class described, a shoe adapted to be applied between the rail and wheel, a swingingly mounted rod having detachable engagement 90 with the shoe, a chain connected to one end of the shoe and passed about a winding drum, releasable means for normally locking the drum to hold the said chain taut, a second chain attached to the intermediate portion of the first chain by one end and to a fixed support by the other, and a compression member fixed in said second chain.

8. In a railway brake of the class described, a shoe adapted to be applied between the rail and wheel, a swingingly mounted rod having detachable engagement with the shoe, a chain connected to one end of the shoe and passed about a winding drum, releasable means for normally locking the drum to hold the said chain taut, a fixed housing, a compression spring in the housing, a stem slideable in the housing to compress the spring, a normally slack chain connected to the stem and to a fixed support, 105 and a normally slack chain connected to the opposite end of the stem and to the first chain.

9. In a railway brake of the class described, a shoe adapted to be applied between the rail and wheel, a swingingly mounted rod having detachable engagement 110 with the shoe, a chain connected to one end of the shoe and passed about a winding drum, releasable means for normally locking 115 the drum to hold the said chain taut, a fixed housing, a compression spring in the housing, a stem slideable in the housing to compress the spring, a normally slack chain connected to the stem and to a fixed support, and a normally slack chain connected to the opposite end of the stem and to the first chain.

the drum to hold the said chain taut, a fixed housing, a compression spring in the housing, a stem slidable in the housing to compress the spring, a normally slack chain connected to the stem and to a fixed support, and a normally slack chain connected to the opposite end of the stem and to the first chain, that chain connected to a fixed support and to the stem being shorter than the

movement permitted to the stem by compression of the spring.

In testimony whereof I affix my signature in presence of two witnesses.

JOHN B. GRAVELLE. [L.S.]
